United States Patent Office

Des. 217,441
Patented May 5, 1970

217,441

CONTAINER FOR FOOD

Amos R. Kanaga, P.O. Box 1033,
San Mateo, Calif. 94403

Filed June 28, 1968, Ser. No. 12,548

Term of patent 14 years

Int. Cl. D9—04

U.S. Cl. D9—232

Fig. 1

Fig. 2

Fig. 3

Fig. 4

Fig. 5

Fig. 6

FIG. 1 is a perspective view of a container for food showing my new design;

FIG. 2 is a perspective view on a reduced scale with the cover open; and

FIG. 3 is an end elevational view with the cover closed and on a scale similar to that of FIG. 1.

FIG. 4 is a plan view of the bottom thereof with the cover closed;

FIG. 5 is a side elevational view with the cover closed; this view showing the side of the container for food opposite to the side shown in FIG. 1; and

FIG. 6 is an end elevational view with the cover closed of the end of the container opposite to the end shown in FIG. 3 and on a scale similar to FIGS. 2 and 5.

I claim:

The ornamental design for a container for food, as shown.
